UNITED STATES PATENT OFFICE.

HUBERT E. ALLEN, OF WHITTIER, CALIFORNIA, ASSIGNOR TO ELLIOTT CORE DRILLING COMPANY, A CORPORATION OF CALIFORNIA.

CORE RETAINER.

Application filed April 27, 1925. Serial No. 26,140.

This invention relates to core retainers for core drills, and is more particularly adapted to a core retainer wherein means are provided for retaining the core within the core-receiving barrel and which means are so constructed and mounted as to effectually retain the core without cutting or damaging the core during the drilling.

In the art of core drilling, when the core has been drilled, it is extremely practical to shut off the water flow and rotate the core drill at a higher rate of speed so as to "burn" the core so that the same will be retained in the core-receiving barrel when the core drill is withdrawn from the bore. This burning of the core drill also burns the cutters from the core drills and necessitates a repair of the core drill for each core taking operation.

It is, therefore, an object of this invention to provide a retaining member adapted to retain the core within the core-receiving barrel so that the necessity of burning the core will be eliminated.

Another object of this invention is to provide core retainers for core drills of simple construction and so mounted that the same will not damage, cut or chop the core in the core-receiving barrel during the taking of the core.

Other objects and advantages of this invention will be apparent from the following detailed description of a preferred embodiment thereof, as illustrated in the accompanying drawings.

In the drawings:

Fig. 1 is a side elevation of a core retainer, illustrating the same as partly in central section, and illustrating a core retaining member mounted within the core retainer of the core drill embodying this invention.

Fig. 2 is a top plan view taken substantially on the line 2--2, Fig. 1.

In the preferred embodiment of this invention illustrated in the drawings, my core retaining member is illustrated as positioned within a core drill constructed in accordance with the copending application, Fay Oliver, Serial Number 9,455, filed February 16, 1925. However, it is to be understood that this invention is adaptable for use in any core drill.

The core retainer of the core drill illustrated in the drawings comprises a barrel 1 which may be a continuation of the drilling

stem and which barrel 1 is screw threaded to the core drill head 2 as illustrated by means of tapered threads 3. A bushing 4 is secured within the interior of the barrel 1 by any suitable means, such as the threads illustrated at 5 and the inner barrel 6 is screw threaded in this embodiment of this invention to the bushing 4. A circumferential shoulder 7 is formed in the body of the head 2 and is provided with a race 8. A ring 9 having a complementary race 10 is adapted to seat upon the shoulder 7 and to be maintained in position by means of the bushing 4. A plurality of fingers 11, of spring steel or a like material, are secured to the ring 9 preferably in recesses 12 by any suitable means such as the rivets 13. The fingers 11 being secured in the recesses 12 so as to provide a flush or even inner surface of the ring 9. The inner surface of the ring 9 is preferably of the same or of slightly less diameter than the inner diameter of the inner barrel 6. Bearing members 14 are mounted within the recesses 7 and 10 and the bearing members are herein illustrated as comprising hardened steel balls. The operation of this core retaining member is the core formed by means of the core drill head 2 passing upward through the ring 9 and into the barrel 6 where the same is engaged by the finger 11, it being understood that the inward diverging of the finger 11 is herein exaggerated for the purpose of illustration.

As the core within the barrel 6 is a continuation of the core being formed by the head 2, the same will tend to remain stationary when the core barrel 6 is rotated so that if the fingers 11 were maintained stationary the same would cut or chop this core and therefore by mounting the fingers 11 upon the ring 9 and providing the bearing member 14 the fingers 11 are permitted to remain at rest or to rotate as the core is rotated, such rotation of the fingers 11 being caused only by the rotation of the core within the barrel 6, it being understood that there is maintained a clearance between the bushing 4 and the upper edge of the ring 9 and a clearance between the outer perimeter of the ring 9 and the core drill head 2.

It will be apparent from the foregoing that I have provided a simple and extremely efficient core retaining member which is easily adaptable to core drills as now manufactured and which is particularly applica-

ble to carry out my invention. However it is to be understood that many modifications may be made therein without departing from the spirit of my invention as set forth in the appended claim.

I claim:

In a core drill, the combination of a core drill head, an outer core barrel screw-threaded to the said head, a core retainer, freely secured within the core drill head and hav-

ing inwardly projecting core retaining fingers, a bushing screw-threaded to the core drill head in position to maintain the core retainer from endwise motion, and a core receiving member screw-threaded to the 15 bushing and having a central passage therethrough into which the said fingers project.

Signed at Compton, California, this 19th day of March, 1925.

HUBERT E. ALLEN.
